UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

MINING APPARATUS.

Application filed April 19, 1921. Serial No. 462,726.

To all whom it may concern:

Be it known that I, NILS D. LEVIN, a citizen of the United States, residing at Columbus, in the county of Franklin and

5 State of Ohio, have invented certain new and useful Improvements in Mining Apparatus, of which the following is a specification, reference being had therein to the accompanying drawing.

10 The present invention relates to certain new and useful improvements in mining apparatus comprising a truck adapted to support a coal cutting machine for transportation from one working place to another and 15 provided with guiding devices by which said coal cutting machine may be conveniently positioned for operation and guided during said operations.

I am aware that machines have been proposed wherein the weight of the entire apparatus, including the cutting mechanism, is carried by the truck not only during transportation but also during the cutting operations. With its weight carried by the truck 25 it is impossible to permit the cutting mechanism to project beyond the outlines of the supporting base through more than a certain relatively small distance, and consequently the width of the room or entry 30 which can be cut by such a machine is quite limited.

In my co-pending application, Serial No. 9,972, filed February 23rd, 1915, and renewed as Serial No. 396,590, is disclosed 35 an apparatus in which the cutting mechanism can be carried upon the truck during transportation and in which it is removable horizontally therefrom without breaking its connection therewith to rest entirely upon the floor of the mine and to be moved horizontally under the guidance and control of the truck to cut a horizontal kerf from one side to the other of a relatively wide room.

40 45 In coal mines break throughs, or connecting passages, are formed at regular intervals in the walls between adjacent rooms and between parallel adjacent entries, through which is maintained the circulation 50 of air necessary to the ventilation of the mines. The formation of these break throughs necessitates the occasional opera-

tion of the cutting mechanism along the side walls of the rooms and entries in lines parallel with their length. By the earlier machines falling within the above definition, the cutting of such break throughs could only be accomplished by entirely disconnecting the cutting mechanism from the truck, and laboriously moving it by means of bars, 55 cables, etc., into the desired cutting position, and after the completion of the cutting operation, moving it back in like manner to a position from which it might be re-mounted upon the truck. Such a mechanism is disclosed in my co-pending application, Serial 60 No. 174,088, filed June 11th, 1917.

It is the especial object of this invention to provide an apparatus in which the cutting mechanism can be carried by the truck 70 during transportation, and in which it is movable horizontally therefrom without breaking its connection therewith to rest entirely upon the floor of the mine and to be moved horizontally under the guidance and 75 control of the truck to cut a horizontal kerf from one side to the other of a relatively wide room, or to cut a horizontal kerf longitudinally of the side walls of a relatively narrow room, and to provide in such 80 apparatus means for maintaining a more complete control of the cutting mechanism than is possible with the devices previously known.

The devices by which I attain this object 85 are fully set forth in the following specification and illustrated in the accompanying drawings of which—

Fig. 1 is a side elevation of the preferred embodiment of my invention showing a coal cutting machine of well known construction 90 loaded for transportation from one working place to another, certain parts being broken away to reveal other parts.

Fig. 2 is a fragmentary side elevation of 95 the devices shown in Fig. 1, showing the coal cutting mechanism in position for cutting across the face of the mine room.

Fig. 3 is a plan view of the devices illustrated in Fig. 2.

Fig. 4 is a side elevation of part of the 100 guiding devices showing the mining machine in position to begin the sumping or entering cut.

Fig. 5 is a plan view of the main base part of the truck with some of the mechanisms carried thereby, the swinging, supporting and guiding devices for the coal cutting mechanism being removed.

Fig. 6 is a plan view of the turn table and tilting frame of the truck.

Fig. 7 is a section taken along the line 7-7 of Fig. 3.

Fig. 8 is a section taken along the line 8-8 of Fig. 3.

Fig. 9 is a section taken along the line 9-9 of Fig. 3.

Figs. 10 to 17 inclusive are diagrammatic plan views of a mine room showing the various methods of operation of this invention.

Like numerals refer to similar parts in the several figures.

In the drawings the numeral 1 indicates, as an entirety, a mining machine adapted to form a horizontal kerf across the coal face, the numeral 2 indicates a truck adapted to travel along the rails 3 of the mine tracks to support said mining machine for transportation and, while still supported upon the track rails, to serve as an abutment for the guiding and controlling devices 4, 5 and 6. The mining machine is of the well known type comprising a main frame 7 adapted to rest upon and slide over the floor of the mine from which projects an elongated cutting mechanism 8 adapted to be thrust longitudinally into the coal and to then be moved laterally to form a kerf therein. Upon the main frame 7 is also mounted the feeding and power transmission devices by which the machine is actuated from a suitable motor 9.

The truck 2 comprises a truck frame 10 having journal bearings 11 in which are rotatable the axles 12 and 13. To these axles are fixed the wheels 14 which support the truck upon the track rails. The axles 12 and 13 are connected together by a suitable sprocket chain 15, and the axle 13 is connected with the truck driving mechanism 16 by a suitable sprocket chain 17. The truck driving mechanism 16 is adapted to be connected with the power devices of the mining machine when the latter is loaded upon the truck in position for transportation, but as these devices are well known in the art and form no part in the present invention further description of them at this time is not thought to be required.

Mounted upon the truck frame 10, for rotation about a vertical pivot 18, is a turn table comprising the rectangular steel plate 19 to the forward edges of which are attached the bearings 20 in which are journaled the trunnions 21 attached to the guide frame 4 midway its length. The guide frame 4 is formed of longitudinally extending angle bars 22 joined together by suitable cross members 23 to form a rectangular

frame which is tiltable from end to end upon the trunnions 21 to permit of its forward end being lowered to proximity with the mine floor.

Pivotedly attached to the forward end of the tilting frame 4, for oscillation in both vertical and horizontal planes, is the guide member 5 which comprises a steel plate 24 adapted to rest upon and slide over the floor of the mine. The plate 24 is of circular outline with a forward rectangular extension, and its lateral and rear edges are reinforced by an angle bar 25 the upwardly projecting flange 26 of which forms, at its forward part, an extension of the guide bars 22 of the tilting frame. Secured to the plate 24 concentric with the curved part of the angle bar 25 is an upwardly extending stud 27 by which said plate is attached to a pivot casting 28 for rotation about a vertical axis. The pivot casting 28 is rotatably attached to a horizontal transverse shaft 29 fixed to the forward end of the tilting frame 4. By this arrangement of parts the guide member 5 is supported by the forward end of the tilting frame 4, clear of the track rails, when the mining machine 1 is in traveling position upon the truck, can adapt itself to the irregularities of the mine floor when the frame 4 is in its tilted position, and may be turned about the pivot 27 to any desired angular position relative to the longitudinal lines of the tilting frame. Formed in the curved part of the flange 26 is a plurality of notches 30 which are adapted to be engaged by the latch bolts 31, attached to the tilting frame, to maintain any preferred angular relation between the longitudinal lines of the frames 4 and 5.

The mining machine 1 rests directly upon, and is slidable longitudinally of, the bottom pan 6 which comprises a steel plate 32 adapted to rest upon and slide over the floor of the mine. The lateral edges of the plate 32 are reinforced by angle bars 33 which constitute skids along which the mining machine slides, and the upturned flanges 34 of these angle bars engage the sides of the mining machine frame 7 to prevent its lateral movement relative to bottom pan. A latch bolt 35 hinged to the frame 7 of the mining machine is adapted to engage with notches 36 in the flanges 34 when the mining machine is in its extreme position at either end of the bottom pan. By the engagement of the latch bolt 35 the machine is held against longitudinal movement in the pan during the lateral cutting operations and during transportation.

The bottom pan 6 is slidable along the guide members 4 and 5 between the upwardly extending flanges 22 and 26, and is automatically locked in its extreme rearward, or traveling position, and in its extreme forward, or operative, position, by

the engagement of the bolts 37 with the apertures 38 or 39 of the side flanges 22 and 26. The bolts 37 are slidable in apertures of the flanges 34 at both sides of the bottom pan, and are connected with an operating lever 40 at opposite sides of its fulcrum bolt 41, so that movement of the lever 40 causes movement of the bolts 37 in opposite directions. A compression spring 42 arranged 10 between a suitable collar 43 on one of the bolts 37 and an upstanding flange 44 of the bottom pan 6 resiliently holds said bolts in their outer position and causes them automatically to engage the apertures 38 and 39. 15 The mining machine 1 is provided with a winding mechanism adapted to wind the feed rope 45 the end of which may be connected to any suitable abutment towards which the machine will be drawn by the 20 winding of the rope. A hook 46, attached to the forward end of the guide member 5, affords such an abutment to draw the mining machine and bottom pan forwardly along the guide members 4 and 5 to position 25 said mining machine upon the mine floor preparatory to cutting the coal. When the mining machine moves forwardly as its center of gravity passes the trunnions 21 the tilting frame 4 tilts, causing the guide member 5 to contact with the floor of the mine. A similar hook 47 is attached to the forward 30 end of the bottom pan 6 to which the feed rope 45 may be connected to cause movement of the mining machine forwardly along the bottom pan to thrust the cutting mechanism 8 longitudinally into the coal to make the sumping, or entering, cut.

An abutment 48 is attached to the rearward end of the tilting frame 4 to which the feed rope 45 may be attached to draw the mining machine rearwardly of the bottom pan, and to draw said machine and bottom pan rearwardly along the guide members 5 and 4 into loading position upon the truck. 45 As the center of gravity of the mining machine passes rearwardly of the trunnion 21 the frame 4 tilts to its horizontal traveling position and the proportions of the parts are such that the weight of the mining machine securely retains them in their proper traveling position during transportation about the mine.

In Figs. 10 to 14 inclusive, I have shown one method of operating this apparatus in a relatively wide room of a coal mine. The truck 2 with the mining machine loaded upon it, as illustrated in Fig. 1 of the drawing, on arriving at the working place, is positioned at a suitable distance from the coal face, as illustrated in Fig. 10. The machine is then rotated upon the turn table 19, to the position illustrated in Fig. 11, so that the cutter arm 8 will extend towards the point at the right hand side of the room at 55 which the cutting is to begin. The feed

rope 45 is then attached to the hook 46 at the forward end of the guide member 5, and the winding mechanism of the mining machine is actuated to draw said mining machine together with the bottom pan 6, forward. As 70 these parts move forward the guiding members 4, 5 and 6 assume the position illustrated in Fig. 12 with the forward end of the bottom pan 6 resting upon the mine floor in close proximity to the face of the coal. 75 The feed rope 45 is then connected to the hook 47 at the forward end of the bottom pan 6 and the cutting mechanism is forced forward to make the sumping, or entering, cut as illustrated in Fig. 13. After the completion of the sumping cut the feed rope 45 is connected to a suitable anchor jack 49 placed adjacent the left hand rib, in the manner well understood in the mining machine art, and the machine swung upon the 80 radius 4, 5 and 6 about the pivot 18 to cut an arcuate kerf in the coal as illustrated in Fig. 14. It is of course obvious that jacks similar to the jack 49 may be placed against any preferred part of the truck to hold it in 85 position as is the common practice with mining machines generally, the number and arrangement of such jacks depending upon local conditions and the opinions of the operator, and it is not thought to be necessary to show such jacks in the drawings. When the cut has been completed across the room, the feed cable 45 may be connected to the abutment 48 upon the tilting frame 4, 90 the machine drawn to the rear of the tilting frame, and the latter rotated to its traveling position in the manner which has been hereinafter described.

Under some circumstances, as for example when cutting at the end of an entry, it is desirable that the side walls shall be maintained in straight lines parallel to the general direction of the entry. In such a case the machine is positioned, as shown in Fig. 15, with the guide member 5 turned to such an angle with the tilting frame 4 that the bottom pan 5 will be approximately parallel with and in close proximity to the right hand rib and locked in that position by the latches 31. The machine is then sumped in the usual manner after which the latch bolts 31 are disengaged from the notches 30 to permit freedom of rotation of the guide member 5 relative to the tilting frame 4. The feed cable 45 is then connected to a suitable jack 50 at the left hand side of the entry and the machine is drawn across the face in a straight line in the same manner as if it were operating entirely independent of the truck and its guiding attachments. The truck 2 is allowed to move freely longitudinally of the tracks and recedes from the face as the tilting frame approaches the longitudinal center line of the tracks and afterwards approaches the face as said tilting 105 110 115 120 125 130

frame passes said center line. After the completion of the cut the machine may be reloaded in the usual manner.

In Figs. 16 and 17 I have illustrated a method of cutting break throughs and pockets in the rib, at right angles to the general direction of the mine chamber. The machine having been unloaded, as previously described, and the guide member 5 rotated relative to the tilting frame 4 to a suitable angle, so that the bottom pan 6 will lie transversely of the mine chamber with its forward end in close proximity to the rib, and locked in that position, the machine may be dumped into the rib as shown in Fig. 16. The feed cable 45 will then be attached to a suitable anchor jack 51 positioned adjacent to the mine wall and the entire machine, including the truck, moved bodily rearward along the tracks thus cutting a kerf in the wall of the rib to the width desired for the break through or pocket. After the completion of this cut the machine will again be loaded as above described.

What I claim is—

1. In a truck adapted to the transportation of a mining machine, the combination with a truck frame, of an elongated supplemental frame attached to said truck frame and rotatable about a vertical axis thereon and tiltable about a horizontal axis positioned midway its length, an extension frame universally flexibly attached to said supplemental frame, and a mining machine supporting and guiding frame adapted to slide longitudinally of said supplemental and extension frames as and for the purpose set forth.

2. In a truck adapted to the transportation of a mining machine, the combination with a truck frame, of an elongated supplemental frame attached to said truck frame and rotatable about a vertical axis thereon and tiltable about a horizontal axis positioned midway its length, an extension frame universally flexibly attached to said supplemental frame, a mining machine supporting and guiding frame adapted to slide longitudinally of said supplemental and extension frames, and means to lock said supporting and guiding frame in either of its extreme positions of longitudinal adjustment as and for the purpose set forth.

3. In a truck adapted to the transportation of a mining machine, the combination with a truck frame, of an elongated supplemental frame attached to said truck frame and rotatable about a vertical axis thereon and tiltable about a horizontal axis positioned midway its length, an extension frame universally flexibly attached to said supplemental frame, a mining machine supporting and guiding frame adapted to slide longitudinally of said supplemental and ex-

tension frames, and means to automatically lock said supporting and guiding frame when it reaches either of its extreme positions of longitudinal adjustment as and for the purpose set forth.

4. In a truck adapted to the transportation of a mining machine, the combination with a truck frame, of an elongated supplemental frame attached to said truck frame and rotatable about a vertical axis thereon and tiltable about a horizontal axis positioned midway its length, an extension frame universally flexibly attached to said supplemental frame, a mining machine supporting and guiding frame adapted to slide longitudinally of said supplemental and extension frames, and means to lock said extension frame in any preferred position of horizontal angular adjustment relative to said supplemental frame.

5. In a truck adapted to the transportation of a mining machine, the combination with a truck frame, of an elongated supplemental frame attached to said truck frame and rotatable about a vertical axis thereon and tiltable about a horizontal axis positioned midway its length, an extension frame universally flexibly attached to said supplemental frame, a mining machine supporting and guiding frame adapted to slide longitudinally of said supplemental and extension frames, an arcuate flange on said extension frame concentric with its pivotal attachment to said supplemental frame, and means on said supplemental frame co-operating with said flange to lock said extension frame in any preferred position of horizontal angular adjustment relative to said supplemental frame.

6. In a truck adapted to the transportation of a mining machine, the combination with a truck frame, of an elongated supplemental frame attached to said truck frame and rotatable about a vertical axis thereon and tiltable about a horizontal axis positioned midway its length, an extension frame universally flexibly attached to said supplemental frame, a mining machine supporting and guiding frame adapted to slide longitudinally of said supplemental and extension frames, an arcuate flange on said extension frame concentric with its pivotal attachment to said supplemental frame and provided with a plurality of notches adapted to engage a latch upon said supplemental frame to lock said extension frame in any preferred position of horizontal angular adjustment relative to said supplemental frame.

7. In apparatus of the class described, the combination of a truck, a horizontally rotatable and vertically tiltable supplemental frame carried by said truck, an extension frame coupled to said supplemental frame for angular movement relative thereto, and a mining machine supporting and guiding

frame slidably longitudinally of said supplemental and extension frame.

8. In apparatus of the class described, the combination of a truck, a horizontally rotatable and vertically tiltable supplemental frame carried by said truck, an extension frame coupled to said supplemental frame for angular movement relative thereto, means for locking said extension frame in any position of adjustment relative to said supplemental frame, and a mining machine supporting and guiding frame slidably longitudinally of said supplemental and extension frames.

15 9. In apparatus of the class described, the combination of a truck, a horizontally and vertically tilttable supplemental frame carried by said truck, an extension frame coupled to said supplemental frame for horizontal and vertical movements relative thereto, and a mining machine supporting and guiding frame slidable longitudinally of said supplemental and extension frames.

20

10. In apparatus of the class described,
25 the combination of a truck, a horizontally
rotatable and vertically tiltable supplemental
frame carried by said truck, an extension
frame coupled to said supplemental frame
for horizontal and vertical movements rela-
30 tive thereto, means for locking said extension
frame in any position of adjustment
relative to said supplemental frame, and a
mining machine supporting and guiding
frame slidable longitudinally of said sup-
35 plemental and extension frames.

40 11. In apparatus of the class described, the combination of a truck, a horizontally rotatable and vertically tiltable supplemental frame carried by said truck, an extension frame coupled to said supplemental frame for horizontal and vertical movements relative thereto, latch devices on said supplemental frame to engage recesses on said extension frame and lock said frames in any 45 position of adjustment, and a mining machine supporting and guiding frame slideable longitudinally of said supplemental and extension frames.

12. In apparatus of the class described,
50 the combination of a truck, a horizontally
rotatable and vertically tiltable supplemen-
tal frame carried by said truck, an extension
frame coupled to said supplemental frame
for horizontal and vertical movements rela-
55 tive thereto, a latch engaging flange on said
extension frame, latch devices on said sup-
plemental frame to engage said flange and
lock said frames in any position of adjust-
60 ment, and a mining machine supporting and
guiding frame slidably longitudinally of
said supplemental and extension frames.

55 13. In apparatus of the class described, the combination of a truck, a horizontally rotatable and vertically tiltable supplemental frame carried by said truck, an exten-

sion frame coupled to said supplemental frame for horizontal and vertical movements relative thereto, a curved latch receiving flange on said extension frame, latch devices on said supplemental frame to engage said curved flange and lock said frames in any position of adjustment, and a mining machine supporting and guiding frame slideable longitudinally of said supplemental and extension frames. 75

14. In apparatus of the class described, the combination of a truck, a horizontally rotatable and vertically tiltable supplemental frame carried by said truck, an extension frame coupled to said supplemental frame for horizontal and vertical movements relative thereto, a mining machine supporting and guiding frame slideable longitudinally of said supplemental and extension frames, and means to lock said supporting and guiding frame in predetermined positions of adjustment on said extension and supplemental frame. 80 85

15. In apparatus of the class described, the combination of a truck, a horizontally rotatable and vertically tiltable supplemental frame carried by said truck, an extension frame coupled to said supplemental frame for horizontal and vertical movements relative thereto, a mining machine supporting and guiding frame slidable longitudinally of said supplemental and extension frames, and means automatically to lock said supporting and guiding frame when it reaches predetermined positions of adjustment on said extension and supplemental frame. 90 95 100

16. In apparatus of the class described, the combination of a truck, a horizontally rotatable and vertically tilttable supplemental frame carried by said truck, an extension frame coupled to said supplemental frame for horizontal and vertical movements relative thereto, a mining machine supporting and guiding frame slidable longitudinally of said supplemental and extension frames, and a spring bolt adapted automatically to lock said supporting and guiding frame when it reaches predetermined positions of adjustment on said extension and supplemental frame. 105 110 115

17. In apparatus of the class described, the combination of a truck, a horizontally rotatable and vertically tiltable supplemental frame carried by said truck, an extension frame coupled to the forward end of said supplemental frame for horizontal and vertical movements relative thereto, means for locking said extension and supplemental frames in any position of angular adjustment, a mining machine supporting and guiding frame mounted for longitudinal movement on said extension and supplemental frame, and means for locking said supporting and guiding frame in a predetermined position.

mined position of longitudinal adjustment on said extension and supplemental frames.

18. In apparatus of the class described, the combination of a truck, a horizontally rotatable and vertically tilttable supplemental frame carried by said truck, an extension frame coupled to the forward end of said supplemental frame for horizontal and vertical movements relative thereto, means for locking said extension and supplemental frames in any position of angular adjustment, a mining machine supporting and guiding frame mounted for longitudinal movement on said extension and supplemental frame, and means automatically to lock said supporting and guiding frame when it reaches a predetermined position of longitudinal adjustment on said supplemental frame.

19. In apparatus of the class described, the combination of a truck, a horizontally rotatable and vertically tilttable supplemental frame carried by said truck, an extension frame coupled to the forward end of said supplemental frame for horizontal and vertical movements relative thereto, means for locking said extension and supplemental frames in any position of angular ad-

justment, a mining machine supporting and guiding frame mounted for longitudinal movement on said extension and supplemental frame, and means automatically to lock said supporting and guiding frame when it reaches a predetermined position of longitudinal adjustment on said supplemental frame.

20. In apparatus of the class described, the combination of a truck, a horizontally rotatable and vertically tilttable supplemental frame carried by said truck, an extension frame coupled to the forward end of said supplemental frame for horizontal and vertical movements relative thereto, means for locking said extension and supplemental frames in any position of angular adjustment, a mining machine supporting and guiding frame mounted for longitudinal movement on said extension and supplemental frame, and means automatically to lock said supporting and guiding frame when it reaches a predetermined position of longitudinal adjustment on said extension and supplemental frame.

In testimony whereof I affix my signature.
NILS D. LEVIN.
